[57] CLAIM

The ornamental design for a pool ball necklace, as shown and described.

DESCRIPTION

FIG. 1 is a front elevational view of a pool ball necklace showing my new design, the broken line showing of a wearer is for illustrative purposes only and forms no part of the claimed design;

FIG. 2 is a front elevational view;

FIG. 3 is a rear elevational view;

FIG. 4 is a partial end elevational view, the opposite end being a mirror image; and,

FIG. 5 is a front elevational view of a pool ball necklace showing a second embodiment of my new design, the views of the first and second embodiments are essentially the same as FIGS. 1-4 except for the number of balls and the numbers thereon. The portion of the chain not shown, in FIGS. 2, 3, 4 and 5, is omitted for ease of illustration.
